CLAIM

The ornamental design for a pneumatic compression controller, as shown and described.

DESCRIPTION

FIG. 1 is a perspective of a pneumatic compression controller, a display screen on the controller and a support for the controller being shown in phantom;

FIG. 2 is a top view of the pneumatic compression controller;

FIG. 3 is a bottom view thereof;

FIG. 4 is a front elevation thereof;

FIG. 5 is a back elevation thereof, fluid outlet ports on the controller being shown in phantom; and,

FIG. 6 is a right elevation thereof, the left elevation thereof being a mirror image thereof.

The broken lines are included for the purpose of illustrating portions of the pneumatic compression controller that form no part of the claimed design.
